UNITED STATES PATENT OFFICE.

CARL J. BETTGER, OF GRAVELBOURG, SASKATCHEWAN, CANADA.

GATE-LATCH.

1,271,655.

Specification of Letters Patent.

Patented July 9, 1918.

Application filed September 24, 1914. Serial No. 863,341.

To all whom it may concern:

Be it known that I, CARL J. BETTGER, subject of the King of Great Britain, residing at Gravelbourg, in the Province of Saskatchewan and Dominion of Canada, have invented certain new and useful Improvements in Gate-Latches, of which the following is a specification.

This invention relates to gate latches of 10 that type which are automatically operated to close the gate after the passage of a vehicle therethrough in either direction, and has for its principal object to provide a simple means which in connection with a 15 sliding gate adapted to be opened by hand and to automatically close through the operating of a weight, spring, or other means, of a latch connected to operating means on both sides of the gate which upon the 20 passage thereover of a moving vehicle, will release and permit the gate to close, thus saving time and relieving the driver of the necessity of descending from the vehicle to close the gate.

25 The above and additional objects are accomplished by such means as are illustrated in the accompanying drawings, described in the following specification and then more particularly pointed out in the claims which 30 are appended hereto and form a part of this application.

With reference to the accompanying drawings, wherein I have illustrated the preferred embodiment of my invention as it is reduced 35 to practice, and throughout the several views of which like characters of reference designate similar parts,

Figure 1 is a view in perspective of a gate such as contemplated by this invention 40 in its open position and set for the automatic closing.

Fig. 2 is a side elevation with parts being shown in section of the matter disclosed in Fig. 1.

45 Fig. 3 is a detail of the vehicle actuated plunger.

Upon reference to the drawings, there will be seen a gate supporting structure comprising the uprights 5, 6 and 7 which are 50 of a sufficient height to support the continuous trackway 8 at such a distance above the ground that the ordinary carriage, wagon or other vehicle can readily pass therebeneath. These uprights are embedded in the 55 ground in the same manner as the usual gate posts and are adapted to be alined with the

fence, it also being noted that fencing is to be interposed between the uprights 6 and 7 although not so illustrated. The automatically closing gate frame 9 consists of a pair 60 of uprights 10 and 11 suitably connected by transverse bars 12 and carrying at their upper ends the track sheaves 13, properly journaled adjacent the extremities of the uprights and being of such construction as to 65 easily run upon the trackway 8. A small upright is secured to the trackway 8 immediately above the upright 5 and also carries a pulley 14 over which the flexible connection 15 is adapted to run, one end of said connection being suitably affixed to the upright 10 of the movable gate member and the other end supporting the counterbalance 16 which is of sufficient weight to overcome 70 the forces of gravity and inertia on the movable gate member 9 unless such member is otherwise secured. As a further means to insure the easy running of this gate member and to prevent its getting out of alinement with the trackway 8 there is provided the 75 roller 17 operating upon the undersurface of the lower transverse member 12 and being carried by the upright 6.

A latch plate 18 is secured upon the lower extremity of the upright 10 of the movable 85 member and operating thereagainst is a spring controlled detent 19 which is vertically mounted between the spaced and integral ears 20 of a supporting plate 21 designed to be secured to the upright 6 adjacent the base thereof. A cotter pin or other securing means 22 transfixes this detent and interposed between such pin and the lower ear 20 is placed the coiled spring 23. The lower end of the detent after passing 90 through the lower ear is enlarged to provide the angular bearing surfaces 24 upon which suitable bell cranks 25 and 26 are adapted to operate under proper conditions.

95 The bell crank 25 is pivoted to the angular ear 27 formed upon one extremity of the supporting plate 21 and the bell crank 26 is pivoted to the main portion of the plate itself in the manner clearly illustrated in 100 the drawings.

Situated a suitable distance from each 110 side of the gate and in direct alinement with the passage therethrough are provided the plunger chambers 28 which are U-shaped in cross section and adapted to receive the plunger plates 29 for vertical reciprocation.

Pivoted to the side of each chamber adjacent the gate is a bell crank 30 having its outermost arm slotted as at 31 to receive a pin 32 carried by the plunger plate 29. As 5 is clearly shown in Fig. 3, suitable resilient means such as the expansible coiled springs 33 are positioned within the chamber 28 to bear upwardly against the plunger plate 29 such upward movement being limited by the slotted arm of the bell crank 30. Any suitable connection 34 which may be a wire, rope, cable or the like connects the free ends of the bell cranks 25 and 26 with their respective bell cranks 30 so that the 10 operation of the gate may be controlled by means of the plunger plates 29.

In practice, the plunger supports 28 are buried in the ground so that their tops shall be flush with the upper surface thereof as 15 shown in Fig. 2 and at a suitable distance such as twenty feet or more from the gate itself so that a vehicle may readily stand between the gate and either plunger 29. The gate being presumably closed, the driver 20 of the vehicle halts the same after the wheels thereof have passed the nearest plunger plate and alighting draws the gate back upon the trackway 8 to the position shown in Fig. 1 at which time the spring 23 will 25 force the detent 19 through the upper ear of the supporting plate 21 so as to bear against the force of gravity exerted upon the counterbalance 16. Owing to the easy running of the movable gate member 9 which 30 has been assured by providing the sheaves 13, the trackway 8 and the roller 17, the driver of the vehicle may easily place the gate in its open position. Upon resuming 35 his seat, he has but to drive through the gate and proceed until the wheels of the vehicle come in contact with the plunger 29 on the far side of the gate at which time the plunger will be depressed against the action of the spring 33 and will accordingly 40 draw down the slotted arm of the bell crank 30 which will be transmitted into an outward movement upon one of the bell cranks 25 or 26 consequently resulting in the depressions of the detents 19 and the consequent 45 release of the movable gate member which will thus be free to act by the pull of the counterbalance 16 and be automatically closed.

Copies of this patent may be obtained for five cents each, by addressing the "Commissioner of Patents, Washington, D. C."

While in the foregoing however, I have thus illustrated in the drawings and described in the specification such combination and arrangement of elements as constitute the preferred embodiment of my invention, I desire to emphasize the fact that I may make such minor changes in the matters of proportion and degree, in later adaptations of my device as shall not alter the spirit of my invention as defined in the appended claims.

What I claim is:

1. A latch release comprising a supporting plate, a spring pressed detent slidable in said supporting plate and normally projecting through and beyond the same, bell cranks pivoted to said supporting plate facing in opposite directions and swinging in the same plane for retracting said detent, one arm of each bell crank bearing directly on the detent, plunger chambers adapted to be sunk in the ground at a distance from 75 said supporting plate and detent and on opposite sides thereof, plungers carried in said chambers, and means for transmitting the motion of said plungers to said bell cranks to release said detent.

2. A latch release comprising a latch member having an angular end, a supporting member for said latch member, bell cranks pivotally mounted upon said supporting member to swing in the same plane, one arm of each bell crank bearing upon the angular end of said latch member, resilient means for normally retaining said latch member in operative position, plungers at a distance from and on opposite sides of said 80 latch member, a supporting member for each of said plungers adapted to be placed across a roadway below the surface of the same, a bell crank connected by one arm to each plunger, and connections between the bell 85 cranks on said plungers and said first named bell cranks to operate the latter when a plunger is depressed and force said latch member into inoperative position.

In testimony whereof I affix my signature 90 in presence of two witnesses.

CARL J. BETTGER.
